ELECTRICALLY OPERATED CALCULATING APPARATUS FOR CONVERTING NUMBERS FROM BINARY TO DECIMAL FORM

George Clifford Hartley and John Ridd Gould, London, England, and Leslie Baines Haigh, West Orange, N. J., assignors to Standard Telephones and Cables Limited, London, England, a British company

Application July 12, 1943, Serial No. 494,283
In Great Britain July 21, 1941

9 Claims. (Cl. 235—61)

1

This invention relates to electrically operated calculating apparatus.

In copending applications, Serial Nos. 494,282 and 492,060, filed July 12, 1943, and June 24, 1943, respectively, there have been described forms of such apparatus for performing calculations on numbers expressed in radix two and the results of the calculation were obtained as a number expressed in radix two. In application, Ser. No. 494,281, filed July 12, 1943 now Patent No. 2,411,540, there is described a form of electrically operated calculating apparatus which automatically converts a number expressed in radix ten into a number expressed in radix two.

Radix ten is the ordinary system of numbers based on the number 10; radix two is a system of numbers based on the number 2. No digit in any number of radix two is ever greater than 1. A succession of numbers may be obtained in radix two by adding 1 to the preceding number in each case, but, whenever the addition of 1 produces 2, 0 is entered for the digit and 1 is carried over to the next left position. For example, numbers in radix two corresponding to 1 to 12 of radix ten are as follows:

Radix ten	Radix two	Radix ten	Radix two
1	1	7	111
2	10	8	1000
3	11	9	1001
4	100	10	1010
5	101	11	1011
6	110	12	1100

The present invention relates to means for obtaining in radix ten the equivalent of a number expressed in radix two. According to the present invention there is provided calculating equipment comprising means for entering thereinto a number expressed in radix two, electrically operated means for computing automatically the number expressed in radix ten which is equivalent to said first mentioned number, and means for rendering the computed number available.

The nature of the invention will be better understood from the following description of three different embodiments thereof taken in conjunction with the accompanying drawings in which

Fig. 1 shows a circuit for converting a number expressed in radix two into a number expressed

2

in radix ten where the latter is known not to exceed two digits;

Figs. 2 and 3 taken together form a complete circuit diagram, with Fig. 2 on the left of Fig. 3, of a calculating equipment into which numbers expressed in radix 2 are entered digit by digit.

Both in Fig. 1 and in Figs. 2 and 3 there are shown electrically operated means, operative in a plurality of stages for computing the number 10 expressed in radix ten which is equivalent to a multi-digit number expressed in radix two which is entered into the equipment.

Figs. 4, 5 and 6, taken together, show yet another form of circuit for converting a number 15 expressed in radix two into a number expressed in radix ten, and in this case the computation is performed in a single stage.

Fig. 7 is a circuit diagram of a subtracting circuit shown in Fig. 1. In the several figures 20 a plurality of relays are shown, these being designated by a letter or letters, followed by a slanting line and a number, the number representing the number of contacts which are physically controlled by the relay. These contacts are designated with the letter or letters of the relay to which they belong followed by a number which distinguishes the contacts of a particular relay from one another. In order to eliminate confusion of wires in the diagram and to make it 25 easier to understand the operation of the circuits, the contacts have been shown in the circuits which they control, rather than adjacent the relays which operate them.

Referring to the drawings, Fig. 1 shows a circuit 30 in which the magnitude of a number expressed in radix two entered therein is automatically expressed as a sum of a series of lesser magnitudes, the circuit including registering means for registering the lesser magnitudes. There are also 35 shown circuits closed by said registering means for rendering available the number in radix ten which is equivalent to the number entered. The means for expressing the magnitude of the number entered as a sum of predetermined lesser magnitudes comprises means for performing an attempted series of subtractions of numbers expressing said lesser magnitudes. In the circuits shown it is assumed that the radix ten number to be computed does not possess more 40 than two digits. Such a number consists of the

over $1N4$ front and $1M4$ front if both $1M$ and $1N$ are operated and over $1N4$ back and $1M4$ back if neither $1M$ nor $1N$ is operated and over $1N3$ back and $1M4$ front if $1M$ is operated and $1N$ is unoperated. The wires marked x and $-$ respectively lead to the circuits for performing subtraction in denomination 2^2 and for indicating on wire $e2$ the value of the digit (i. e. whether 1 or 0) appearing in denomination 2^2 in the result. The circuits in denominations 2^3 , 2^4 , and 2^5 are exact duplicates of those in denomination 2^2 .

As will appear presently, for the arrangements shown in Fig. 1, the maximum remainder that can appear is nineteen, i. e. 10011 in radix two and thus no wire a^2 has been shown in that figure. The arrangements for giving a digit in denomination 2^6 of the remainder have accordingly been omitted in Fig. 7. The contacts of relays $5M$ and $5N$ for extending ground to wire $b2$ could also have been omitted.

The first operation after the relay DA operates is the closing of the contacts $DA5-DA12$ so that a combination of the relays $IA-IG$ can be operated by the grounds on the input lead $a3-g3$. Suppose that the minuend entered be 110011, the radix two equivalent of ninety-nine. When the relay DA operates in the example given, relays IA , IB , IF (not shown) and IG will be operated since the grounds representing the number 110011 puts grounds on leads $a3$, $b3$, $f3$ and $g3$. This closes contacts $IA2$, $IB2$, $IF2$ (not shown) and $IG2$ which connect grounds to relays $6M$, $5M$, $1M$ and $0M$ and operate them.

The relay DA also acts to enter the number eighty, i. e. 101000, in radix two, as the subtrahend by applying grounds to leads $a1$ and $c1$ through contacts $DA3$ and $DA4$, respectively. This operates relays $6N$ and $4N$.

The remainder 10011, which is the radix two equivalent of 19, is indicated by ground applied to wires $c2$, $f2$, and $g2$ as follows; ground through $0M1$ front, to wire $g2$; ground through $1M2$ front, $1N1$ back, to wire $f2$; ground through $1N2$ back, $1M4$ front, $2N4$ back, $2M4$ back, $3N4$ back, $3M4$ back, $4M2$ back, $4N1$ front, to wire $c2$.

No grounds appear on the wires $e2$ and $d2$ because neither relay in each of these denominations is operated and there is no ground on the wire X . The circuit for wire $b2$ includes $5N1$ back, $5M2$ front, through $5N4$ back to open contact at $5M4$ back and also through $4M4$ back to open contact at $4N4$ back. There is therefore no ground on lead $b2$.

Because of the operation of relays $5M$, $6M$, and $6N$ ground is applied at $5N3$ back, $5M4$ front, $6N4$ front, $6M4$ front, to line p . Line n has no ground and the circuit can be traced through $6M3$ front, $6N2$ front, $5M3$ front, to open contact to $5N2$ front.

Wires $b2-g2$ are connected by contacts $XX5-XX10$ to relays $RB-RG$, (three only of which are shown), which relays thus store the remainder temporarily. In the example given, since the remainder is nineteen, represented by 10011 in radix two, relays RC , RF (not shown), and RG operate.

In this case the remainder is positive, and ground appears on the wire p , as already explained. The ground on the wire p operates relay X through $XX4$ front, and at contacts $X1$, just below and to the right of the relay RG , completes a locking circuit for such of the relays $RB-RG$ as are operated. At contacts $X3$, (extreme right of the figure), a circuit is completed for relay SA over front contacts $DA13$, front

contacts $X3$, front contacts $XX1$ to ground. Relay SA operates to record that subtraction was possible and locks over contacts $SA1$ to ground on the start lead ST . At contacts $X2$ the circuit for relay XX is broken. This relay is shunted by a condenser and a resistance so that it has a delayed release time which is accurately controlled. The release of relay XX releases relay SA at $XX1$ front. When relay XX has released, the condenser QA , (upper left of figure), which is in a charged condition, having been connected to battery through front contacts $XX2$, discharges over back contacts $XX2$, front contacts $DA1$, and one winding or relay DB . Relay DB operates its contacts $DB1$ and thus connects its second winding to the ground on the start lead ST and operates fully, opening at $DB2$ the circuit of the relay DA , which releases, and at contacts $DB3$ preparing a circuit for the operation of relay DC . At contacts $DA5-DA12$ the original circuits for the input relays IA to IG are broken. The operation of relay X also removes the locking circuit for relays $IA-IG$ at $X1$ and $X4$ back and also puts ground on the operating circuit at $X4$ front for a new combination of these relays to be operated, which combination is determined by the relays $RB-RG$ which are operated. Such of the relays which are not to be in the new combination, (these being IA and IB), release, and the relays which are to be in the new combination either operate or hold over the new circuit. The relays IF and IG hold over $RF2$ (not shown) and $RG2$, while relay IC operates over $RC2$. The original combination of the M relays in Fig. 7 then assumes a new setting, representing a new minuend, to correspond with the combination of relays $IA-IG$ which are operated. Thus, since relays IC , IF , and IG are operated, their contacts directly operate relays $4M$, $1M$ and $0M$, while $6M$ and $5M$ are released. Relay XX in releasing breaks the circuit of relay X , by opening front contacts $XX4$. The release of this relay is delayed by a condenser and resistance in shunt to its winding, for the purpose of allowing time for the contacts $DA5-DA12$ to open and relays $IA-IG$ to release before the ground is put back on their locking circuits at back contacts $X4$ and $X1$. The relays $IB-IG$ act to store the remainder. Thus, in the example chosen, relays IC (not shown), IF (not shown), and IG are operated. There is no need to provide a relay for the digit of the remainder corresponding in denominational value to that registered by relay IA , since such digit should not appear in the remainder. When relay X releases, relay XX is re-operated.

The relay DB at contacts $DB5$ and $DB6$, shown at the right of subtracting circuit S , now applies ground to the wires $b1$ and $d1$, in order to subtract or attempt to subtract the number 101000 which is the equivalent in radix two of the number forty. Grounds on these wires operate the relays $5N$ and $3N$ in the circuit of Fig. 7, and relays $6N$ and $3N$ release because of the release of DA . Relay X or relay Z will be operated according as the subtraction is, or is not possible. In this particular example, the subtraction was not possible and relay Z operates while relay X does not operate. SB is not operated because relay X is not operated and the previous remainder remains stored on relays $IA-IG$. The operation of relay Z releases relay XX at 21 back which in turn releases X at $XX3$ front, it having been prepared for operation through front contacts $DB3$. This releases re-

lay DB and grounds are removed from relays 5N and 3N at contacts DB5 and DB6 and these relays release. At the next stage relay DC at contacts DC5 and DC6 applies ground to the wires c1 and e1 respectively, which operates relays 4N and 2N, so that an attempt is now made to subtract 10100 the radix two equivalent of twenty. The release of relay Z operates relay XX again over Z1 back and DC4 front. Subtraction is not possible, relays 4N and 2N being operated and ground being extended to wire n to operate relay Z over 3N3 front, 2M3 back, 3N2 back, 3M3 back, 4N2 front, 4M3 front, 5N2 back, 5M3 back, 6N2 back, 6M3 back, and XX3 front to the Z relay. A similar sequence of operations takes place, relay XX releasing when relay Z operates, and relay DD is operated. The operation of relay DD releases relay DC and applies ground to leads d1 and f1 through contacts DD4 and DD5. The release of relay DC releases relays 4N and 2N and the operation of relay DD operates relays 3N and 1N to attempt a subtraction. With relays 4M, 1M, and 0M still operated, and relays 3N and 1N operated for a subtrahend of 1010, a subtraction is possible and a remainder of 1001 the radix two equivalent of 9, is registered by the application of ground to wires d2 and g2. Ground is extended to wire d2 over 1N4 front; 2N4 back, 2M4 back, 3M2 back, and 3N1 front. Ground is removed from lead f2 by the operation of relays 1M and 1N. Ground is removed from lead C2 by the release of 4N. The removal of grounds from c2 and f2 releases relays RC and RF and the ground on d2 operates relay RD. Relay 0M remains operated to hold relay RG operated.

The release of relay XX also releases relay Z and the release of relay Z reoperates relay XX. Ground is also extended to wire p to indicate that subtraction was possible from 4N3 back, 4M4 front, 5N4 back, 5M4 back, 6N4 back, 6M4 back. This ground operates relay X over XX4 front and thus when relay DD has operated over contacts DC3 front in the same manner as described above, relay SD operates over DD5 front, X3 front, XX1 front to ground and locks over SD1 front to the ground on start wire ST. After this sequence of operations, on the release of relay XX, relay DE operates and locks to the start lead ST, and releases relay DD at DE2 back. The remainder registered on relays RB-RG will be a four digit radix two number less than ten. The relays SA, SB, SC, SD form a set of storage elements, one for each of the magnitudes eighty, forty, twenty and ten, each of said relays being placed in operated or non-operated condition to register the presence or absence of its corresponding magnitude in the series of magnitudes of which the number entered is built up. The front contacts DE4 close circuits for the indicator lamps I over contacts of the relays SA-SD for the tens digit and relays RD-RG for the units digit to display the number in radix ten which is the equivalent of the original number entered in radix two. The relays RD, RE and RF for temporarily storing digits of the successive remainders are not shown but certain of their contacts are shown in the circuits of the lamps I for indicating the value of the final units digit. Thus in the example given in which relays SA and SD were operated and also remainder relays RD and RG, ground is extended over DE4 front to the lamp 9 in the tens array over SA2 front and SD6 front, and to lamp 9 in the units array over RD3 front and RG7 front, indicating that the original

number entered in radix two was equivalent to 99 in radix ten.

It will be apparent to one skilled in the art that the circuit shown in Fig. 1 may be extended to compute automatically numbers of more than two digits. In the case where it is known that the result will be a number in radix ten of not more than three digits, the experimental subtractions are first made with 1100100000 (eight hundred), 110010000 (four hundred), 11001000 (two hundred) and 1100100 (one hundred), followed by the attempted subtractions described above, and similarly the circuit may be extended to deal with large numbers of digits.

The same process may be extended to the conversion of decimals with the exception that the result must, in general, be an approximation. By working to an appropriate number of significant figures, however, it is possible to achieve any desired degree of accuracy. The process in this case is to start by attempts to subtract the radix two equivalents of the radix ten numbers 0.8, 0.4, 0.2 and 0.1. These are to ten significant figures .1100110011, then .0110011001, .0011001100, and .0001100110. With decimals it will not be possible to read a radix ten number directly from the remainder expressed in radix two. It will, therefore, be necessary to continue to subtract .08, .04, .02, .01, etc., until the remainder is negligible in the standard of accuracy required in the answer.

In the circuit shown in Figs. 2 and 3 means is provided for transforming each digit of the number entered into an equivalent number in radix ten and for computing from said equivalent numbers the number expressed in radix ten which is equivalent to the number entered.

The numbers in radix two are entered, digit by digit commencing with the digit of highest denomination. A pair of keys is provided for this purpose and is shown in the bottom left hand corner of Fig. 2, one key for each of the two possible digital values 0 or 1. These keys can clearly be replaced by the contacts of coupling relays or multi-position switches arranged to connect the circuit to any kind of device which represents a digit of a radix two number by grounding one of two wires.

At the left hand side of Fig. 2 is shown a set of sequence relays controlling the sequence of computing operations, which latter are carried out by means of relay circuits shown on the right hand side of Fig. 2 and in Fig. 3. Provision is made for as many denominations in radix ten as may be required for the radix two numbers that are to be converted, i. e. one denomination for radix two numbers up to and including 1001, two denominations up to 1100011, three denominations up to 111100111 etc.

The value of a digit entered in radix two is recorded by operating one of two relays PA and PB; PA for the value 0 and PB for the value 1. It will be observed that the equivalents in radix ten of the radix two numbers 0 and 1 are the same numbers 0 and 1, respectively. The operation of PA or PB thus represents the value 0 or 1, respectively, in radix ten also.

As soon as the first digit 1 of a radix two number to be converted is keyed, the equivalent radix ten number 1 is entered, from contacts of PB, into the units denomination of the calculator, and stored therein. (If the first digit 0 is keyed in error, there is no change in the calculator because none of the regular calculating relays are operated by the entrance of a 0 before a 1; only

the incidental sequence relays at the left of Fig. 2 are operated and released in their predetermined sequence.) The second digit of the radix two number is then keyed and calculation begins.

Considered in radix two, the keying of this second digit implies that the number so far keyed has become, by that keying action, a two-digit number, with the first digit transferred from denomination 2^0 , which it previously occupied, to denomination 2^1 , and the second digit placed in denomination 2^0 , i. e. a number having a total value equal to 2 times the value of its first digit, plus the value of its second digit.

Now, the equivalent of the radix two number 10 in radix ten is the number 2. It follows, therefore, that the radix ten equivalent of the two-digit radix two number keyed is equal to twice the radix ten equivalent of the first digit keyed, plus the radix ten equivalent of the second digit keyed, i. e. to twice the first digit keyed, plus the second digit keyed. Similarly, when the third digit of the radix two number is keyed, the radix ten equivalent of this is equal to twice the radix ten equivalent of the two-digit number previously keyed, plus the third digit keyed, and so on. Thus, the conversion of a number expressed in radix two into a number expressed in radix ten can be carried out by a process of repeated doubling and adding. For example, the radix ten equivalent of the radix two number 1011101 may be computed as shown in Table 1.

Table 1

Stage	Radix ten	Radix two
I	Insert 1st digit 1	1 = 1
II	Double and add 2nd digit 0	2 = 10
III	Double and add 3rd digit 1	5 = 101
IV	Double and add 4th digit 1	11 = 1011
V	Double and add 5th digit 1	23 = 10111
VI	Double and add 6th digit 0	46 = 10110
VII	Double and add 7th digit 1	93 = 1011101

operated condition of any 1A relay represents the value 1 in the denomination concerned, of a 2A relay the value 2, a 4A relay the value 4, and a 5A relay the value 5.

5 A plurality of indicator lamps are shown along the lower edge of the figures. These are arranged to indicate the numbers 0-9 in each of the thousands, hundreds, tens, and units denomination. They are controlled by contacts of the A relays 10 1, 2, 4 and 5 in each denomination in a manner to be hereinafter described.

When a number stored on the A relays is to be doubled, calculation takes place in two stages. First, the number stored is transferred from the

15 A relays to the corresponding B relays. Second, the holding circuit of the A relays is opened, and the latter immediately re-operate in a new combination, representing the number which is the double of that previously stored, 20 directly determined by contacts of the B relays. "Carry over" from one denomination to another (which, it will be observed, can never exceed value 1 when a number is doubled) is determined by contacts of the 5B relays acting in the 25 next higher denomination.

When the value 1 is to be added in the units denomination, this calculation takes place concurrently with the doubling process. The value 1 is treated as a carry over of 1 from a lower 30 denomination, not provided, to the units denomination, and the change is effected by contacts of the keying relay PB, acting in the units denomination in the same way as the above-mentioned contacts of the 5B relays act in the 35 other denominations.

The doubling process may be repeated for any number of radix two digits, subject only to the capacity of the calculator.

The following Table 2 shows the relays operated in any denomination, when each of the 40 ten possible stored numbers is doubled, with and without the addition of 1 carried over from the next lower denomination.

Table 2

Number stored	B relays operated	Stored number doubled	A relays operated	Stored number doubled plus 1 carried over	A relays operated
0	None	0	None	1	1A
1	1B	2	2A	3	1A 2A
2	2B	4	4A	5	
3	1B 2B	6	1A 5A	7	2A 5A
4	4B	8	1A 2A 5A	9	4A 5A
5		10	None	11	1A
6	5B	12	2A	13	1A 2A
7	1B 5B	14	4A	15	
8	2B 5B	16	1A 5A	17	2A 5A
9	1B 2B 5B	18	1A 2A 5A	19	4A 5A

The circuit is arranged to carry out such computations rapidly and automatically.

In each denomination there is a set of four aggregate relays, 1A, 2A, 4A and 5A (1THA, etc., in the thousands denomination, 1TA, etc., (not shown), in the hundreds, 1TA, etc., in the tens, and 1UA, etc., in the units), and a set of four aggregate-retaining relays 1B, 2B, 4B and 5B, (1THB, etc., in the thousands denomination the 70 1HB, etc., not shown, in the hundreds, 1TB, etc., in the tens, and 1UB, etc., in the units). The

Detailed circuit operation

It is supposed that an operator desires to obtain the radix ten equivalent of the radix two number 1011101.

The operator throws key "Start" and relay ST 70 operates. This key remains in the start position during the entire calculation.

This causes indicator lamps to light and display the radix ten number 0000. The circuit for these lamps is made from ground through back contacts C1, front contacts ST4 and the 75

11

back contacts of the 5A, 4A, 2A and 1A relays in each denomination.

The operator depresses key 1 for the first digit. PB operates and locks to PB1, over back contacts M2 and T1 and front contacts ST3. AP operates over M1 back, PB6 front AL1 back ST1 front, to ground and locks to AP1 and T2 back and the same ground. C operates through AP2 front. Display ceases, open at C1.

1UA operates from ground on C2 front, over 4UB2 back, 2UB2 back, and PB2 front. M operates over C4 front, PB6 front, AL1 back, ST1 front, to ground, and locks to M1 front. Relay T is a slow acting relay and now operates through C1 front, slowly enough to allow 1UA time to operate before T.

AP, open at T2, releases. 1UA holds over 1UA1 front, AL2 back, ST2 front, AP3 back, to ground. C, open at AP2, releases. T, open at C1, releases.

PB, open at C5 releases, as soon as key 1 is allowed to restore. 1UB operates to C3 back over 1UA2 front. The units lamp 1 and lamps 0 in the other denominations light in circuits from ground on C1 back, over ST4 front, 5UA3 back, 4UA3 back, 2UA3 back, 1UA3 front, lamp 1 to battery for the unit digits and similar circuits for lamps 0 in the other denominations and display the number 0001, the radix ten equivalent of the radix two number so far keyed (stage I in Table 1). M releases as soon as PB6 opens.

It will be observed that, as a consequence of the operation of PB, AP, C and T operated and released again in turn in self-timing circuits, that while C was operated the value 1 was entered into the calculator, and that when C released again the new number 1 was displayed.

On observing this number, the operator depresses key 0 for the second digit. PA operates and locks to PA1, over back contacts M2 and T1, now closed and ST3 front to ground. AP operates to PA2 and locks to AP1, followed by C, and display ceases. 1UB holds over 1UB1 front, AP3 front, to ground. 1UA, open at C2 back, releases. 2UA operates to C2 front, over 1UB2 front and 2UB3 back. M operates over C4 front, PA2 front, AL1 back, ST1 front to ground and locks over M1 front to the same ground. T operates over C1 front, slowly enough to allow 2UA time to operate.

AP, open at T2, releases, followed by C and T. 2UA holds to AP3 back. PA, open at C5, releases as soon as key 0 is allowed to restore. 1UB, open at C3 front, releases. 2UP operates to C3 back, over 2UA2 front. The units lamp 2 and lamps 0 in the other denominations display the radix ten number 0002 (stage II), units lamp 2 being energized over 1UA4 back, 2UA3 front, 4UA3 back, 5UA3 back, ST4 front, C1 back, to ground. M releases as soon as PA2 opens.

It will be observed that, as a consequence of the operation of PA, AP, C and T once more operated and released in turn, that while C was operated the number 1 previously stored was doubled, and that when C released again, the new number 2 was displayed.

The operator depresses key 1 for the third digit. PB operates and locks. AP operates and locks, followed by C, and display ceases. 2UB holds to AP3 front. 2UA, open at C2 back, releases. 5UA operates to C2 front, over 4UB2 back, 2UB2 front, 1UB3 back and PB5 front. M operates by the closing of C4 and locks over M1. T operates, slowly enough to allow 5UA time to operate.

12

AP releases, followed by C and T. 5UA holds to AP3 back. PB releases as soon as key 1 is allowed to restore because of the opening of C5. 2UB, open at C3 front, releases. 5UP operates to C3 back, over 5UA2 front. The unit lamp 5, and lamps 0 in the other denominations, display the number 0005 (stage III), lamp 5 of the units being lit over 2UA4 back, 1UA5 back, 4UA4 back, 5UA3 front, ST4 front, C1 back, to ground. M releases as soon as PB6 opens.

It will be observed that, as a consequence of the operation of PB, AP, C and T once more operated and released in turn, that, while C was operated, the number 2, previously stored, was doubled, and the number 1 entered was added to the product, and that when C released again, the new number 5 was displayed.

The operator depresses key 1 for the fourth digit.

PB and AP operate and lock, followed by C, and display ceases. 5UB holds to AP3 front. 5UA, open at C2 back, releases. 1UA operates to C2 front, over 4UB2 back, 2UB2 back, and PB2 front. 1TA operates to C2 front, over 4TB2 back, 2TB2 back and 5UB2 front. M operates and locks. T operates, slowly enough to allow 1UA and 1TA to operate.

AP, C and T release. 1UA and 1TA hold to AP3 back. PB releases as soon as key 1 is allowed to restore.

5UB, open at C3 front, releases. 1UB and 1TB operate to C3 back, over 1UA2 and 1TA2, respectively. The units lamp 1, the tens lamp 1, and lamps 0 in the other denominations, display the number 0011 (stage IV). M releases as soon as PB6 opens.

It will be observed that, as a consequence of the operation of PB, AP, C and T once more operated and released in turn, that while C was operated the number 5, previously stored, was doubled, and the number 1 entered was added to the product, that carryover of 1 from the units to the tens denomination was effected automatically, and that when C released again the new number 11 was displayed.

The operator depresses key 1 for the fifth digit.

PB, AP, C, M and T operate and display ceases. 1UB and 1TB hold to AP3 front. 1TA, open at C2 back, releases.

1UA, although open at C2 back, holds to C2 front over 4UB2 back, 2UB2 back, PB2 front. 2UA operates to C2 front over 1UB2 front and PB3 front. 2TA operates from ground on C2 front over 1TB2 front and 2TB3 back.

AP, C and T release. 1UA, 2UA and 2TA hold to AP3 back. PB releases as soon as key 1 restores, followed by M. 1TB, open at C3 front, releases. 1UB, although also open at C3 front, holds to C3 back, over 1UA2 front. 2UB and 2TB operate to C3 back, over 2UA2 and 2TA2, respectively. The units lamp 3, the tens lamp 2, and the lamps 0 in the other denominations, display the number 0023 (stage V).

The operator depresses key 0 for the sixth digit. PA, AP, C, M and T operate, and display ceases. 1UB, 2UB and 2TB hold to AP3 front. 2UA and 2TA, open at C2 back, release. 1UA holds to C2 front, over 4UB2 back, 2UB2 front, 1UB3 front and PB2 back. 5UA operates to C2 front over 4UB2 back, 2UB2 front and 1UB3 front. 4TA operates to C2 front over 4TB2 back, 2TB2 front, 1TB3 back, and 5UB5 back.

AP, C and T release. 1UA, 5UA and 4TA hold to AP3 back. PA releases as soon as key 0 restores, followed by M.

2UB and 2TB, open at C3 front, release. 1UB holds to C3 back over 1UA2. 5UB and 4TB operate to C3 back over 5UA2 and 4TA2, respectively. The units lamp 6, the tens lamp 4, and lamps 0 in the other denominations, display the number 0046 (stage VI). The circuit of the units lamp 6 may be traced over 2UA5 back, 1UA5 front, 4UA4 back, 5UA3 front, ST4 front, C1 back, to ground. The circuit for the tens lamp 4 may be traced over 4TA3 front, 5TA3 back, 10 ST4 front, C1 back, to ground.

The operator depresses key 1 for the seventh and last digit. PB, AP, C, M and T operate, and display ceases.

1UB, 5UB and 4TB hold to AP3 front. 5UA, open at C2 back, releases. 1UA holds to C2 front, over 4UB2 back, 2UB2 back and PB2 front. 2UA operates to C2 front over 1UB2 front and PB3 front. 4TA holds to C2 front over 4TB3 front and 5UB4 front. 5TA operates to C2 front over 4TB2 front.

AP, C and T release. 1UA, 2UA, 4TA and 5TA hold to AP3 back. PB releases as soon as key 1 restores, followed by M. 5UB, open at C3 front, releases. 1UB and 4TB hold, and 2UB and 5TB operate to C3 back, over 1UA2, 4TA2, 2UA2 and 5TA2, respectively. The units lamp 3, the tens lamp 0, and lamps 0 in the other denominations, display the number 0093, the radix 10 equivalent of the complete radix 2 number keyed, (stage VII). The units lamp 3 operates over 1UA4 front, 2UA3 front, 4UA3 back, 5UA3 back, ST4 front, and C1 back, to ground. The tens lamp 0 operates through 4TA4 front, 5TA3 front, ST4 front, C1 back, to ground.

It will be observed that while C was last operated, the number 46, previously stored, was doubled, and the number 1 entered was added to the product, and that carry-over of 1 from the units to the tens denomination was again effected automatically.

It has been shown in the above example how the values 1, 2 and 3 in one or other denomination are doubled without the addition of 1 carried over from the next lower denomination, and how the values 1, 2, 4, 5 and 6 are doubled, with 1, carried over from the next lower denomination, added to the product. The manner in which the other possible values of a digit of a number expressed in radix ten are also doubled by the circuits shown will be apparent from the drawing and it is not thought necessary to describe such operations in detail.

Figs. 4, 5 and 6 form a circuit diagram of circuits for automatically calculating the number expressed in radix ten which is equivalent to any number having up to twelve digits in radix two. The three figures form one complete circuit diagram, different contacts of the several relays appearing in each of the three figures, identified by reference characters which indicate the relay to which they belong. The digits of the radix two number are entered simultaneously into the calculator by applying ground to such of the wires a-1, top of Fig. 4, as represents digits having the value 1. Relays A-L are thereby energised to represent the digital values 1 in the respective denominations.

A number expressed in radix two and having n digits is equal to $(a)2^n + (b)2^{n-1} + (c)2^{n-2} + \dots$ etc., where a, b, c , etc., are the values of the respective digits and can be 0 or 1. Thus the successive digits that have the value 1 in a twelve digit number are equivalent to 2048, 1024, 512, 256, 128, 64, 32, 16, 8, 4, 2 and 1 respectively. In

the embodiment of the invention shown in Figs. 4, 5 and 6 each digit of a number expressed in radix two is transformed into an equivalent number in radix ten and the number expressed in radix ten which is equivalent to the number expressed in radix two is computed from the said equivalent numbers. Figs. 4, 5 and 6 show circuits by means of which such of the numbers 2048, 1024, etc., as correspond to the several denominations of the radix two number are added to produce the result of the addition in radix ten.

The circuits may also be considered as comprising means for automatically expressing the magnitude of the number entered as a sum of a series of predetermined lesser magnitude, relays A-L constituting registering means for registering the particular series of magnitudes 2048, 1024, etc., that are contained in the number entered. Circuits are closed by these relays to render available (by display on a series of lamps) the number in radix ten which is equivalent to the number entered.

The contacts of the relays A-L form chain circuits for carrying out the addition of the numbers or magnitudes that they represent, carry over relays being provided to carry over values from one denomination to another that arise as a result of the addition.

Consider first the circuits for the units lamps shown at the bottom of Fig. 6. Since each of the relays A-L represents by its operation a number having a units digit of value other than zero, contacts of all the relays A-L appear in the circuit. Since the order of addition of the magnitudes is immaterial, the order of connection of the contacts of the relays is altered from the order in which the relays are connected to the wires a-l in order to effect economy in carry over relays, as will be apparent later.

When all the relays A-L are in unoperated condition, a circuit is completed for the lamp displaying digital value 0. Each of the relays A-L, other than relays A, E, I and B has five sets of contacts in Fig. 6, the moving contacts of which are connected by five incoming leads to the contacts shown next above in the figure.

The operation of relay L, representing 1 in the units column, changes over the connection of its five incoming leads from lamp 0 to lamp 1, 2 to 3 and so on. A ground appearing on one of these incoming leads will therefore light a lamp representing an even value if L is not operated, or an odd value if L is operated.

The operation of relay K representing 2 in the units column changes over its five incoming leads from 0 to 2, 2 to 4, etc., if L is unoperated or from 1 to 3, 3 to 5, etc., if L is operated. Thus the operation of relay K adds 2 to the conditions represented by the operation of other relays. The contact set K5 should change over from 8 to 10. This is done by causing it to change over from 8 to 0 and at the same time causing the operation of a relay TK inserted in series in the circuit.

Relay J represents 4 in the units column and has contacts connected to change over from each contact of K to the next set but one which gives the effect of adding 4 to the number represented by the conditions of the contacts shown above it. Similarly contacts of relay G representing, when operated, the number 32 which is 2 in the units column and contacts of relay C representing when operated 512 which is also 2 in the units column, are connected so that each adds 2 to the number represented by the contacts shown above it. Relay J in representing a change over from 6 to 10

15

by its contacts **J4**, or from 8 to 12 by its contacts **J5** operates a relay **TJ**. In like manner relays **G** and **C** in representing a change over from 8 to 10 by contacts **G5** or **C5** respectively operate a relay **TC**.

Considering now the part of the units chain from and including contacts of relay **C** to the lamps, whatever combination occurs in the operations of relays **C**, **G**, **J** and **K** the sum of the units digits represented by these relays cannot exceed ten so that the figure carried over to the tens column by their combined operation cannot exceed 1. The same relay **TC** therefore is caused to be operated by contacts **C5** and by contacts **G5** and the operation of either **TC** or **TJ** is caused to operate **TK** which by its operation indicates a carry over of 1 to the tens denomination for all the four relays **C**, **G**, **J** and **K**.

Relay **H** represents 16 and therefore changes over the connections to the next but two sets of relay **C** contacts. There are three change overs which may necessitate a carry over of 1 to the tens denomination, viz. from 4 to 10, from 6 to 12, or from 8 to 14, and accordingly there are three windings included in the circuits which effect these change overs, two windings of relay **THA** and one winding of relay **TH**.

Contacts of relay **F** which represents 64 are wired similarly to contacts of relay **J**, and include in the circuits completed by their change overs, two windings of relay **TF**. Since the carry over represented by the combined operation of relays **H** (units digit 6) and **F** (units digit 4) cannot exceed 1, **TH** is used as the carry over relay and is operated either over its own upper winding or by front contacts **TF1** or front contacts **THA1**.

Relay **D** represents 256 and relay **B** 1024. The contacts of relays **D** and **B** are therefore arranged similarly to those of **H** and **F** respectively, (since they have 6 and 4, respectively, in the units column), with carry-over relays **TD**, **TD** and **TDA**. Operation of relay **TD** thus represents a carry over of 1 to the tens denomination in respect to the sum of the units digits represented by relays **D** and **B**.

Each of the relays **A** (2048), **E** (128) and **I** (8) represents 8 in the units column. The contacts of these relays are so arranged that they add 8, 6 or 4 according as one, two or all three of the relays are operated. Contacts **A1**, **E1** and **I1** normal extend ground to the moving contacts **B1** to add 0. Contacts **A1** operated, **E2** normal and **I3** normal or contacts **A1** normal, **E1** operated and **I3** normal or contacts **A1** and **E1** normal and **I1** operated extend ground to contacts **B4** to add 8. Contacts **A1** and **E2** operated and **I2** normal extend ground over winding of **TE** to **B3**; contacts **A1** operated, **E2** normal and **I3** operated extend ground over winding of **TI** to **B3**; contacts **A1** normal, **E1** operated and **I3** operated extend ground over a second winding of **TI** to contacts **B3** add 6 in the units denomination whilst registering by the operation of **TE** or **TI** a carry over of 1 to the tens denomination. Contacts **A1**, **E2** and **I2** all operated extend ground over the winding of **TE** and the upper winding of **TI** to contacts **B2** to add 4 and register a carry over of 2 to the tens denomination.

It will be seen that, by arranging the contacts of those relays that represent a units figure of 8 at the end of the chain remote from the lamps, a considerable saving in carry over windings is effected. If these relays were at the other end of the chain five contact sets and four carry

16

over windings for each relay would have been needed.

When a number expressed in radix two is entered on the relays **A**—**L**, Fig. 4, the units column is added up immediately by the units chain shown in Fig. 6 and the resultant units digit appears on one of the lamps shown at the bottom of Fig. 6 whilst one or more carry over relays in series may be operated. For example, upon the radix two number 101010101011 being entered, relays **A**, **C**, **E**, **I**, **K** and **L** will be operated and a circuit will be closed from ground, **A1** front, **E2** front, winding of **TE**, **I2** front, winding of **TI**, **B2** back, **D3** back, **F3** back, **C3** front, **G4** front, **J5** back, **K5** front, lower winding of **TK**, **L1** front, lamp for value 1, battery. Relays **TE**, **TI**, and **TK** operate to register a carry over of 3 to the tens denomination and lamp 1 lights.

The contacts of the relays **TI**, **TD**, **TH**, **TK** and **TE** form a contact chain, as shown in Fig. 4 for relays **ZT**, **YT** and **XT**. Any one of the carry over relays operated, causes the operation of **ZT**, any two together the operation of **YT**, any three together the operation of both **YT** and **ZT** on their second windings in series, any four operate **XT** and all five together operate **XT** and **ZT** in series.

The relay chain for the tens digit, Fig. 5 is arranged somewhat differently from that for the units digit. Relays **I**, **J**, **K** and **L** do not represent any tens digit. This is because the number 9 in radix ten is the highest number with a single digit and is equivalent to 1001 in radix two. Therefore, the four relays **I**, **J**, **K** and **L** must be used for the number 9 and in consequence contacts of these relays do not appear in the chain. Several of the relays **A**—**H** represent numbers having an odd tens digit and the carry over total from the units may be odd. These odd digits are therefore considered as consisting of an even digit plus 1, e. g. **H** represents 0+1 and **D** represents 4+1 whilst in an odd carry over total the 1 is represented already by **ZT**. An auxiliary tens contact chain is formed for relays **ST**, **RT** and **QT** (Fig. 4) to add up the figures 1 so obtained, and consists of contacts of **D** representing (4+1), of **G** representing 2+1, of **C** representing 0+1, **H** representing 0+1 and **ZT** representing 1 in the carry over figure. This chain operates relays **ST**, **RT** and **QT** in such a way that **ST** represents 1, **RT** represents 2 and **QT** represents 4.

Thus in Fig. 5 all odd digits in the tens addition are replaced by one odd digit stored on **ST**, and even digits stored on **YT**, **XT**, **RT** and **QT**. The remainder of the chain of Fig. 5 is formed on the same plan as the units chain. Contacts of **ST** act like those of **L** in the units chain. Contacts of **RT** and **YT** are connected so as each to add 2, those of **QT** and **XT** to add 4, contacts of **A** (representing 2048) to add 4, contacts of **D** (256) to add 4 (=5-1), contacts of **F** (64) to add 6, contacts of **G** (32) to add 2 (=3-1), of **E** (128) and **B** (1024) also to add 2.

Carry over relays **HR**, **HQ**, **HX**, **HA**, **HD** and **HF** are inserted in the chain to register the carry over to the hundredths denomination. A third winding on relay **HF** and carry over relay for contacts of **B**, **E**, **G** and **F** are avoided by locating these contacts at the commencement of the chain. The maximum carry over figure from tens to hundreds is 2, but as not many contacts are required it is not worth while to combine the carry over relays as was done for the units chain.

Taking as an example the same number entered as was referred to above, a circuit is closed over

contacts of the three carry over relays TE, TI and TK as follows (Fig. 4): Ground, TI₁ front, TD₂ back, TH₂ back, TK₂ front, TE₃ front, lower winding of YT, upper winding of ZT to battery. Relays YT and ZT operate. A circuit is closed from ground, D₁₁ back, G₉ front, C₉ front, H₈ back, ZT₃ front, windings of RT and ST to battery. Relays RT and ST operate. A circuit is then closed from ground, (top of Fig. 5), B₅ back, E₃ front, G₁ front, F₈ back, D₈ back, A₄ front, XT₅ back, QT₅ back, YT₅ front, upper winding HR, RT₁ front, ST₂ front, lamp 3 to battery. The lamp for tens digit 3 lights and relay HR operates to register a carry over of 1 to the hundreds denomination.

A contact chain is formed from contacts of the carry over relays HF, HD, HA, HX, HQ, and HR for relays ZH and YH (Fig. 4) by means of which ZH may be operated to store a carry over of 1 and YH a carry over of 2.

An auxiliary hundreds chain is formed to sum the figures 1 obtained from the odd hundreds digits and from a tens carry over figure of 1. Contacts of relays C, E and ZH appear in this chain and operate relay SH for 1, RH for 2 or RH and SH in series for 3 (Fig. 4). The main hundreds chain (Fig. 4) is now formed on the same plan as for the tens and units chains. Contacts of SH represent an addition of 1, contacts of RH and YH each an addition of 2, contacts of C an addition of 4 (5-1) and of D an addition of 2. Only one carry over relay MR is required since the chain is so short.

Taking again the same radix number as before 101010101011, the tens carry over relay HR completes a circuit from ground, HF₁ back, HD₁ back, HA₁ back, HX₁ back, HQ₁ back, HR₁ front for relay ZH which operates. A circuit is then closed from ground, C₁₁ front, E₆ front, ZH₃ front for relays RH and SH in series, which relays operate. A circuit is then closed from ground, D₁₂ back, C₅ front, YH₃ back, RH₃ front, SH₄ front for lamp No. 7 which lights.

Finally the thousands chain is formed from contacts of relays A and B and of the hundreds carry over relay MR. Contacts of MR operated add 1, contacts of A operated add 2 and contacts of B operated add 1. Taking the same example as before a circuit is closed from ground, B₆ back, A₇ front, MR₃ back for lamp No. 2. The complete number displayed is thus 2731. The total time needed to display this complete number is inappreciable to the eye and is estimated to be one fifth of a second maximum.

It will be clear that it does not matter for the final result whether the relays A-L are operated simultaneously or in any particular order. Thus the radix two number could be entered digit by digit, either commencing with the digit of highest denomination or with the digit of lowest denomination or in any order. The circuits readjust themselves to indicate the radix ten number corresponding to the radix two number set up at the time.

What is claimed is:

1. Calculating equipment comprising means for entering therein by individual digits a number expressed in radix two, electrically operated means for automatically separating said number into numbers of predetermined magnitudes the sum of which is equal to or less than the entered number, registering means for registering said magnitudes, and circuits closed by said registering means for rendering available the number in

radix ten which is equivalent to the sum of said series of numbers of predetermined magnitudes.

2. Calculating equipment as claimed in claim 1 in which the means for automatically separating said number into a series of predetermined magnitudes comprises means for performing an attempted series of subtractions of numbers expressing said magnitudes in decreasing order of magnitude, commencing with a subtraction from said first mentioned number and continuing with subtractions from either the said first mentioned number or from the remainder resulting from a previous subtraction according as the previous subtrahend was greater or less than the minuend.

15 3. Calculating equipment as claimed in claim 1 in which a set of storage elements is provided one for each of said magnitudes, each of said elements being placed in one condition or another to register the presence or absence of its corresponding magnitude in the said series of magnitudes.

20 4. Calculating equipment as claimed in claim 1 in which said registering means comprises a plurality of storage elements and each of said storage elements serves to register by its condition the value zero or one for the digits of each number of said series of numbers of predetermined magnitudes and said storage elements close contacts in chain circuits which indicate the sum of the 25 said series of numbers of predetermined magnitudes expressed in radix ten.

25 5. Calculating equipment as claimed in claim 1 in which said registering means comprises a plurality of storage elements and each of said storage elements comprises a relay for each 30 denomination of the digits of the number to be entered and serves to register by its condition the value 0 or 1 for a digit of said first mentioned radix two number, the said relays being operated for digital values of 1, and in which said registering means comprises a relay for each of the series of numbers of predetermined magnitudes and contacts of said relays are arranged in chain circuits to render available the 35 digits of the equivalent number in radix ten by applying ground to appropriate wires to represent the different digits.

40 6. A calculating apparatus comprising means for entering thereinto a number expressed in radix two by individual digits, means for performing an attempted series of subtractions of a series of predetermined numbers expressing magnitudes in decreasing order of magnitude and for carrying out said subtractions where possible

45 comprising a first group of relays including one relay for each digit of the number entered, a second group of relays including one relay for each digit of the number entered, a second group of relays including one relay for each digit except the units digit for the numbers to be subtracted and a plurality of difference relays operated by circuits including the contacts of said first and second group of relays, means to register whether or not the subtraction of each successive predetermined number is possible, and means controlled by said registering means and said difference relays to express the said radix two number as the sums of the numbers successfully subtracted and the remainder, respectively.

50 7. A calculating apparatus comprising means to enter thereinto a number expressed in radix two, electrical means for automatically attempting a succession of subtractions of a series of predetermined numbers expressing diminishing magnitudes from said entered number and for

carrying out said subtractions where possible, means to register whether or not a subtraction is possible each time a subtraction is attempted, means controlled by said registering means to cause succeeding subtractions to be made either from said first mentioned number or from the remainder resulting from a previous subtraction according as the previous subtrahend was greater or less than the minuend, means to store the remainder after the last subtraction and means controlled by said registering means and said remainder storing means to add the number successfully subtracted and the remainder after the last subtraction and to represent the sum in radix ten.

8. A calculating apparatus as described in claim 7, in which the predetermined numbers to be subtracted are $10^{n-1}A$, $10^{n-1}B$, $10^{n-1}C$, $10^{n-1}D$, $10^{n-2}A$, $10^{n-2}B$, $10^{n-2}C$, $10^{n-2}D$, $10^{n-3}A$, $10^{n-3}B$, $10^{n-3}C$, $10^{n-3}D$, and a series of successive terms with decreasing powers of 10 until a remainder expressed in the terms 10^0A , 10^0B , 10^0C , 10^0D is obtained; where n equals the number of digits in the first subtracted number and A, B, C, D are equal to 8, 4, 2, and 1, respectively.

9. A calculating apparatus as described in claim 7, in which the predetermined numbers to be subtracted are $10^{n-1}A$, $10^{n-1}B$, $10^{n-1}C$,

$10^{n-1}D$, $10^{n-2}A$, $10^{n-2}B$, $10^{n-2}C$, $10^{n-2}D$, $10^{n-3}A$, $10^{n-3}B$, $10^{n-3}C$, $10^{n-3}D$, and a series of successive terms with decreasing powers of 10 until a remainder expressed in the terms 10^0A , 10^0B , 10^0C , 10^0D is obtained; where n equals the number of digits in the first subtracted number and A, B, C, D are integers arranged in descending order of magnitude, which integers, either alone or in selected combinations, have the values 1, 2, 3, 4, 5, 6, 7, 8, 9, and 10.
